UNITED STATES PATENT OFFICE.

GUSTAVE S. DE BLANC, OF NEW ORLEANS, LOUISIANA.

STREET-CAR FARE-BOX.

SPECIFICATION forming part of Letters Patent No. 299,207, dated May 27, 1884.

Application filed March 5, 1884. (No model.)

To all whom it may concern:

Be it known that I, GUSTAVE S. DE BLANC, a citizen of the United States, residing at New Orleans, Parish of Orleans, and State of Louisiana, have invented certain new and useful 5 Improvements in Street-Car Fare-Boxes, of which the following is a description.

Figure 1 is a perspective view from the front. Figs. 2 and 4 are side elevations from opposite 10 sides on a reduced scale, and Figs 3 and 5 are front and rear elevations on the same scale as Figs. 2 and 4.

My invention relates to fare-boxes for street-cars; and it consists in combining a bell with 15 the fare-box, which bell is so arranged in relation to the orifice or chute through which the fare is inserted that the latter in falling strikes the bell and gives an audible signal to the driver and passengers.

20 In the drawings, A B C D is the fare-box, which in dimension is preferably about five by twenty-four inches at its sides, and ten by twenty-four on its face and back.

E is the chute through which the fare is inserted, and F is a bell or gong sustained upon 25 a horizontal bar just beneath the spout of the chute, so that the fare in falling from the chute strikes the bell or gong and gives an audible signal.

30 G is a glass or metallic plate forming the upper transverse partition or door, which plate is sustained upon pivots at its ends and is subject to reversion by pulling a string or wire thereto attached.

H is a metallic or wooden plate placed below the plate G, and forming also an adjustable door or partition. This plate is subject to reversion only by the starter by means of a 35 knob, which is covered by a locked plate.

I is the metallic or wooden drawer placed 40 below plate H.

In the front of the fare-box is a glass pane, *s r u t*, through which the driver can inspect the fares. On the side of the box there is a glass pane, *o n p q*, through which light from 45 a lamp shines at night, as in Figs. 4 and 5, and *j k l m* is a larger glass pane facing inside the car, through which the interior of the fare-box may be visible to the passengers.

I do not confine myself to any particular 50 proportion of the fare-box or its plates and panes, as these will be varied to suit the varying conditions of the application or different sizes of cars.

Having thus described my invention, what 55 I claim as new is—

The combination, with a fare-box having an orifice or chute for the introduction of the fare, of a bell or gong placed beneath the discharge of said chute or opening to be struck by the 60 fare as it drops from the chute, as and for the purpose described.

G. S. DE BLANC.
